UNITED STATES PATENT OFFICE.

AMOS F. DIXON, OF NEWARK, NEW JERSEY, ASSIGNOR TO WESTERN ELECTRIC COMPANY, OF NEW YORK, N. Y., A CORPORATION OF ILLINOIS.

PRINTING-TELEGRAPH RECEIVER.

1,103,133.

Specification of Letters Patent. Patented July 14, 1914.

Application filed January 9, 1913. Serial No. 741,119.

To all whom it may concern:

Be it known that I, Amos F. Dixon, a citizen of the United States, residing at Newark, in the county of Essex and State of New Jersey, have invented a certain new and useful Improvement in Printing-Telegraph Receivers, of which the following is a full, clear, concise, and exact description.

This invention relates to printing telegraphs and more particularly to a printing telegraph receiving apparatus and system wherein the type selections and the various other necessary operations are controlled by a plurality of current impulses imparted over a single line conductor.

The object of this invention is to provide a receiver of the above class wherein all the necessary functions are performed in a reliable and efficient manner at a high rate of speed.

To the above end, means are provided for distributing a series of current impulses to a plurality of type selecting magnets and operation controlling relays. A rotatable type shaft carrying the characters is likewise provided, together with a plurality of magnet controlled members which by changes in their relative location secure the positioning of the type shaft to print any desired character.

This invention will be fully understood from the following description taken in connection with the accompanying drawing in which the system of connections is shown diagrammatically, and so much of the apparatus as is necessary to a complete understanding of the device is shown in perspective.

The system herein disclosed is operated preferably by various combinations of five positive and negative impulses. The impulses arriving over a main line conductor L from a distant transmitting station pass through the windings of a polarized relay 1 to ground. The relay 1 is provided with an armature 2 connected to a grounded source of energy 3 and adapted, upon its attraction by an impulse of the proper polarity, to engage a front contact 4. The contact 4 is connected to a conducting ring 5 of a current distributor 6 provided with a rotatable arm 7 which is driven by a suitable source of power in the direction of the arrow. The arm 7 is provided with a pair

of outer insulated contact brushes which are 55 adapted to make engagement with a series of commutator bars 11, 12, 13, 14 and 15, connecting them consecutively with the ring 5. The arm 7 is likewise provided with a pair of inner insulated contact brushes 60 engaging a current distributing ring 8, which is connected to a grounded source of energy 9, and a series of commutator bars 10. Arm 7 is constantly rotated, by any desired means, at such a velocity that the outer 65 pair of brushes is interconnecting the first commutator bar of a set with ring 5 upon the receipt of the first impulse of a combination from the transmitting station; the second bar and ring 5 upon the receipt of 70 a second impulse, etc., throughout the cycle of impulses for each selection. This synchronous movement and the means for accomplishing it are well known in the art and will not be further described. As the 75 arm 7 rotates about its axis, battery is therefore connected consecutively to the various commutator bars 11, 12, 13, 14 and 15 by the outer set of brushes when the armature of relay 1 is against the front contact 4, 80 and to the commutator bars 10 by the inner set of brushes.

In the diagrammatic representation of the circuit shown, only one receiving instrument is connected to the current distributor 6, although it is readily understood that other receiving instruments may be similarly connected to the idle commutator bars so that a number of instruments may be operated to receive several distinct messages being transmitted over the single line conductor L.

The commutator bars 11, 12, 13, 14 and 15 are connected respectively to relays 21, 22, 23, 24 and 25 which control the required 95 operations, with the exception of the type selections, and to type selecting magnets 31, 32, 33, 34 and 35, by means of branch conductors 36, 37, 38, 39 and 40.

A type wheel 45 on which the characters 100 are located in a double row is carried by a rotatable type shaft 46 which may be driven as hereinafter described by a spring 47 in the direction shown by the arrow. The spring 47 is kept under tension by 105 means of a motor 48. Concentrically with the type shaft 46 are five movable disks 51, 52, 53, 54 and 55, each of which is provided

with a series of notches 56. There is one notch in each of the disks corresponding to each vertical line of characters carried by the type wheel 45 and each line of notches 5 is provided with a pivoted spring tensioned type selecting lever 65 which is adapted, under certain conditions to be hereinafter explained, to engage with a contact arm 66 carried by the type shaft 46. Each of 10 the selecting magnets 31, 32, 33, 34 and 35 is provided with a spring tensioned armature 70, having a lever 71 which is connected to one of the aforementioned disks 51, 52, 53, 54 and 55 respectively. Thus, when the 15 armature of any of the type selecting magnets is attracted, the corresponding disks are moved through a small angle and whenever one or more of the disks are moved so that a continuous vertical line of notches 20 is presented to one of the levers 65, the spring thereof tends to force the inner end of the corresponding lever upward into a position to be engaged by the rotating arm 66. The type wheel may thereby be arrested 25 in a position to present any desired character to the printing platen.

The levers 65 are restored to their original position and there held between character selections by release levers 72 and 73 pivoted 30 at 74 and 75, and having the centrally projecting ends thereof normally lowered to depress said levers 65, by means of springs 76 and 77. Upon the energization of release magnets 78 and 79, however, the magnetic pull overcomes the spring tension and 35 the centrally projecting ends of the release levers 72 and 73 are raised, releasing all of the type selecting levers 65, only one of which, however, may become operative. Each 40 of the operation controlling relays 21, 22, 23, 24 and 25, starting relay 26, the selecting magnets 31, 32, 33, 34 and 35, and the release magnets 78 and 79 is provided with a holding winding which receives current 45 through the back contacts and the armatures of a clearing out relay 80. The circuit for the magnets may be traced from ground at selecting magnet 35 through magnets 34, 78, 33, 32, 79 and 31 in series in the order 50 named, the right hand armature of the clearing out relay 80 to battery 81 and ground. The circuit for the relays may be traced from grounded battery 81, left hand armature of clearing out relay 80, holding windings of relays 26, 25, 24, 23, 22 and 21 in 55 series in the order named to ground. The current thus passing through the various magnets and relays assists the operating windings thereof in pulling up the respective 60 armatures, thereby increasing the rapidity of operation, and is sufficient to hold the armatures in attracted position after the operating current is removed. Upon the energization of the clearing out relay 80, the 65 circuit of the holding coils is broken and

the displaced armatures of the relays and type selecting magnets are restored to normal position by the retracting springs thereof.

A sufficient description of the system and apparatus may be obtained from a description of a particular type selection and the various operations such as the spacing, line feeding, etc.

Assume that the sending apparatus at a distant station is transmitting a series of impulses for selecting the character D and further assume that the character D is selected by five impulses combined in the following order: positive, negative, negative, positive, negative. Upon the receipt of the first impulse, the outer brushes of the arm 7 of the distributor connect the commutator bar 11 with the distributing ring 5 and as each succeeding impulse is received from the distant station, the arm 7 is moved by its source of power to the next succeeding segment. Assuming that the polarized relay 1 attracts its armature only upon the receipt of positive current, it will be understood that upon the receipt of the first impulse in the selection of character D, the armature 2 is attracted against its front contact 4 and current will flow from grounded battery 3, contact 4, ring 5, commutator bar 11, conductor 36, in multiple through relay 21 and selecting magnet 31 to ground. Both the armatures of relay 21 and magnet 31 are attracted, the latter moving the selecting disk 51 through a small angle. As hereinbefore explained, the current passing through the holding windings of the relays and magnets is sufficient to hold any of the armatures thereof which have been attracted by current through the operating winding. The armatures of relay 21 and magnet 31 are therefore held in advanced position. The second and third impulses being negative current over the line L, the armature 2 rests against its back contact while the arm 7 moves to the commutator bars 12 and 13. Consequently during the second and third impulses no current flows through the distributor. The fourth impulse being positive over line conductor L, the armature 2 again moves against the front contact 4 and current flows from grounded battery 3, contact 4, ring 5, segment 14, conductor 39, in multiple through relay 24 and selecting magnet 34 to ground. The relay 24 and the magnet 34 attract their armatures, the latter moving the disk 54 through a small angle. The armatures are retained in attracted position as hereinbefore described. The fifth impulse being negative, no current flows from the distributor. The movement of the disks 51 and 54 has presented a continuous vertical line of slots 56 before the selecting lever 65 which corresponds to the position of the character D upon the type wheel 45.

After the outer brushes of the arm 7 have

passed the commutator bar 15 the inner set of brushes connects the distributing ring 8 with one of the commutator bars 10 which is connected by a conductor 90 in multiple through the operating windings of the starting relay 26 and the release magnets 78 and 79. Current thereupon flows from grounded battery 9, ring 8, commutator bar 10, conductor 90 in multiple through the operating windings of relay 26 and release magnets 78 and 79 to ground. The release magnets 78 and 79 attract their armatures, forcing the inner ends of the release levers 72 and 73 upward against the tension of the springs 76 and 77, allowing the lever 65 which has been selected as hereinbefore described, to raise its inner end into a position to engage the arm 66 carried by the type shaft. The operation of the starting relay 26 closes a circuit from ground at the armature of relay 26, armature of a start-control relay 92, conductor 93 starting magnet 94, conductor 95, left hand armature of the clearing out relay 80, to battery 81 and ground. The starting magnet 94 thereupon attracts its armature 100, causing a dog 101 carried thereby to be disengaged from a ratchet wheel 102 firmly secured to the type shaft 46. The type shaft thereupon rotates in the direction of the arrow until the arm 66 engages the elevated inner end of the selected type lever 65. Upon the engagement of lever 65 and arm 66, a circuit is closed from ground 103, lever 65, arm 66, conductor 104, printing magnet 105, conductor 106 through the operating winding of space-lock relay 107, conductor 108, through the clearing out relay 80 to battery 81 and ground. The printing magnet 105 attracts its armature 110, forcing a printing platen 111 against the paper printing the selected character D.

The circuit traced through the winding of the clearing out relay 80 causes said relay to attract both its armatures, breaking the circuit for the start magnet 94 for the holding windings of relays 21 and 24, the type selecting magnets 51 and 54 and the release magnets 78 and 79, the armatures of which thereupon are retracted, causing the selecting apparatus to assume its normal position. The attraction of the armatures of clearing out relay 80 also closes a circuit for a retractor relay 153 which, upon pulling up its armature, closes a circuit from ground, armature of retractor relay 153, conductor 154, retractor magnet 155 to grounded battery 156. The retractor magnet pulls up its armature, rotating the type shaft 46 through a small angle in a direction opposite to its normal direction of rotation. The contact between the arm 66 and the lever 65 is broken, opening the circuit for the printing magnet and the clearing out relay.

The space-lock relay in pulling up its armature closes a locking circuit for itself

from battery 130, spacing magnet 131, conductor 132, armature and holding winding of space-lock relay 107, armature of carriage return relay 133 to ground. The space magnet 131 attracts its armature 135, causing a stepping pawl 136 carried thereby to engage the teeth of a ratchet wheel 137, advancing said wheel through the space of one tooth. The ratchet wheel 137 carries a drum 138 upon which is wound a cord 139 connected to a paper carriage 140. As the cord 139 is wound upon the drum 138, the carriage 140 is moved along a square rod 141 to present a clean portion of the paper before the printing platen, and the cord 142 attached to the opposite end of the carriage 140 winds a retracting spring 143 through the agency of a drum 144. The space lock relay insures the operation of the spacing magnet irrespective of the length of the operating impulse and its armature remains locked up until the armature 135 of the spacing magnet 131 is attracted sufficiently to cause an insulated pin 150 carried by said armature to cause the engagement of springs 151. The engagement of the springs 151 causes the holding winding of the space lock relay 107 to be short circuited through a conductor 152 and the space lock relay thereupon releases its armature, opening the circuit through the spacing magnet 131.

If it is desired to provide a space without the printing of a character, a combination of impulses is transmitted over the line conductor L to cause the operation of a spacing relay 157. This is accomplished by the transmission of two negative impulses followed by a positive and then two negatives. The first two impulses have no other effect upon the relay 1 than to force the armature 2 against the back contact in case the next preceding impulse was positive, and consequently no current flows through the distributor. The third impulse closes a circuit from grounded battery 3, contact 4, ring 110, 5, commutator 13, conductor 38, in multiple through relay 23 and selecting magnet 33 to ground, and since the remaining impulses are negative, no further current flows through the distributor. The attraction of the armature of selecting magnet 33 alone does not present a continuous vertical line of slots in the disks before any of the selecting levers 65, and consequently, none of said levers is in a position to be released. The relay 23 attracts its armatures, preparing a circuit from battery 160, armatures and back contacts of relays 21 and 22, armature and front contact of relay 23, conductor 161, space relay 157, conductor 162, armatures and back contacts of relays 24 and 25, coil of the start-control relay 92, and the armature of relay 26. After the arm 7 of the distributor 6 has moved beyond the commutator bar 15, a circuit is closed by the

inner brushes from battery 9, ring 8, commutator bar 10, conductor 90, in multiple through the operating windings of relay 26 and release magnets 78 and 79 to ground. 5 The magnets 78 and 79 raise the inner ends of the release levers 72 and 73, but, since as hereinbefore described, none of the levers 65 are before a continuous line of slots, none of the ends of said levers are raised. 10 The attraction of the armature of relay 26 completes the circuit just traced through the space relay 157 and the start control relay 92. The start control relay 92 is very rapid in its operation and opens the circuit for 15 the starting magnet 94 before the same has time to attract its armature, thus preventing the rotation of the type shaft. The attraction of the armature of the space relay 157 closes a circuit from ground at the armature 20 of carriage return relay 133, armature and front contact of space relay 157, operating winding of space-lock relay 107, winding of the clearing out relay 80, and battery 81 to ground. The clearing out relay 80 and the 25 space lock relay 107 attract their armatures, the former opening the circuit for the holding winding which returns the displaced armatures to normal position, and the latter causing the operation of the space magnet 30 131 as hereinbefore described.

It will be noted that the characters carried by the type wheel 45 are in two horizontal rows and that the upper row is normally in a position to present its characters to the printing platen 111. If it is desired to print any character from the lower row, a series of impulses is imparted over the line conductor to cause the operation of a shift magnet 170. This is accomplished by the transmission of five impulses composed of two positives, a negative and two positives. The positive impulses cause the consecutive closing of circuits through the relays 21, 22, 24 and 25 and the selecting 40 magnets 31, 32, 34 and 35. The operation of the selecting magnets, however, does not cause a continuous vertical line of slots in the selecting disks to be presented before any selecting lever 65, and consequently 45 none can become operative. The operation of the relays 21, 22, 24 and 25 prepares a circuit from battery 160, armatures and front contact of relays 21 and 22, armature and back contact of relay 23, conductor 171, 50 figures relay 172, conductor 173, front contacts and armatures of relays 24 and 25, coil of start-control relay 92, to armature of relay 26. This circuit is completed upon the energization of the relay 26 by current passing from battery 9 through the ring 8 and the commutator bar 10 as hereinbefore described. When the relay 26 attracts its armature, current flows through the figures relay 172 which attracts its armature, closing a circuit from battery 81, winding of the 55

clearing out relay 80, conductor 108, resistance 165, conductor 174, armature of the figures relay 172, conductor 175, winding of a figures-lock relay 176, armature of a letters relay 177, conductor 178, armature and back contact of carriage-return relay 133, to ground. The clearing out relay 80 and the figures-lock relay 176 attract their armatures, the operation of the latter causing the closing of a circuit from battery 180, winding of shift magnet 170, armature and winding of figures-lock relay 176, armature of letters relay 177, conductor 178, armature and back contact of carriage-return relay 133 to ground. The operation of the former 75 removes the current from the holding windings of the operated relays and magnets, returning this apparatus to normal. The current flowing through the shift magnet 170 causes it to attract its armature 185, forcing a roller 186 upward, and since the type wheel rests thereon, the type wheel is moved upward to present the lower row of characters to the printing platen. The action 80 of the figures-lock relay 176 causes the continued energization of the shift magnet 170 until current is sent over the line to cause the unshifting thereof, or until the carriage is returned to its normal position. 85

The unshifting is accomplished by sending five positive impulses over the line conductor, causing the attraction of the armatures of all the relays 21, 22, 23, 24 and 25. Upon the energization of relay 26 a circuit is completed from battery 160, front contacts and armatures of relays 21, 22, and 23, conductor 187, letters relay 177, conductor 173, front contacts and armatures of relays 24 and 25, winding of the start-control relay 92, armature and front contact of relay 26 to ground. The letters relay 177 attracts its armature, opening the circuit through the figures-lock relay 176, deenergizing the shift magnet 170 whereupon a spring 188 lowers the roller 186, which allows the type wheel 45 to assume its normal position in which the upper row of type is presented to the platen. 100

To return the carriage to the beginning of a line a series of impulses is transmitted whereby the relay 24 is caused to attract its armature. After the operation of relay 26 a circuit is closed from battery 160, back contacts and armatures of relays 21, 22 and 23, conductor 190, carriage return relay 133, 105 operating winding of carriage-lock relay 191, conductor 192, armature and front contact of relay 24, armature and back contact of relay 25, winding of start-control relay 92, armature and front contact of relay 26 to ground. The attraction of the armature of the carriage return relay 133 completes a circuit from ground at armature and front contact of carriage-return relay 133, conductor 108, clearing out relay 80, battery 81 110

to ground. The action of the clearing out relay 80 causes the selecting apparatus to be returned to its normal position. The attraction of the armature of carriage-return-lock relay 191 causes the closing of a circuit from ground through the holding winding, armature and front contact of carriage-return-lock relay 191, conductor 195, carriage return magnet 196, to grounded battery 197. The carriage-return-lock relay 191 is, therefore, held in its operated position until the carriage has completely returned, whereupon the holding circuit therefor is opened as hereinafter described. The energization of the carriage-return magnet 196 causes the attraction of armature 198 thereof, which removes a holding pawl 199 from the teeth of a ratchet wheel 137. The energy stored up in the spring 143 during the forward movement of the carriage thereupon becomes effective to return the carriage to the beginning end of a line. As the limit of the carriage return is reached, an insulating pin 201 carried by the ratchet wheel 137 causes the engagement of contact springs 202, which short circuit the holding winding of the carriage-return-lock relay 191 through a conductor 204. The carriage-return-lock relay is thereupon deenergized and the carriage return magnet 196 releases the holding pawl 199 which becomes effective to arrest the return movement as the carriage is stepped forward, for a line of print.

If the figure-lock relay 176, had been energized at the time of the transmission of current for the return of the paper carriage, the energizing circuit thereof would have been broken by the armature and front contact of the carriage-return relay 133. It will, therefore, be understood that the upper row of characters is always presented to the printing platen upon the return of the paper carriage to the beginning end of a line.

In order to feed the paper from line to line, it is necessary to cause the energization of a line feed relay 210 which, upon the attraction of its armature, closes a circuit from ground at armature and front contact of the relay 210, conductor 211, line feed magnet 212, battery 213 to ground. The energization of the line feed magnet 212 causes the attraction of armature 214 and thereupon a stepping pawl 215 engages a ratchet wheel 216 which is firmly secured to the rod 141, rotating the paper carriage. When the armature 214 reaches the limit of its movement, an insulating pin 218 carried thereby causes the engagement of contact springs 219 which effects a deenergization of the coils of the line feed magnet 212 by completing a circuit through the conductors 174 and 108 and the winding of clearing-out relay 80, battery 81 to ground. The clearing-out relay attracts its armatures, breaking the holding circuit for the

energized relay and magnets and the apparatus is restored to its normal position.

What I claim is:

1. A printing telegraph receiver comprising a rotating type wheel shaft, a plurality of pivoted notched disks surrounding said shaft, a plurality of pivoted spring-tensioned levers grouped about said shaft and co-operating therewith and with said disks to selectively arrest said shaft, a release magnet, a lever actuated by said magnet normally acting on said pivoted levers against their spring tension to prevent co-operation with said shaft and said disks but arranged to become inactive to allow co-operation between said shaft, pivoted levers and disks. 70

2. A printing telegraph receiver comprising a rotatable type wheel shaft, an arm thereon, a plurality of movable notched disks encircling said shaft, a plurality of pivoted levers having two extensions one co-operating with said disks and the other projecting centrally to co-operate with said arm whereby said disks may selectively present a continuous line of notches before one of said levers to arrest said shaft, a pair of release magnets, and a lever actuated by each of said magnets having centrally projecting portions normally acting upon the centrally extending portions of said pivoted levers to prevent the co-operation of said disks, pivoted levers and arm, but arranged to be actuated upon the energization of said magnets to allow co-operation of said disks, 100 pivoted levers and arm whereby said shaft may be selectively arrested. 90

3. In a printing telegraph receiver, the combination of a current distributor, a plurality of circuits connected thereto, magnets in said circuits, a plurality of pivoted disks, one for each magnet and controlled thereby, a rotatable type shaft carrying the characters, a plurality of levers selectively controlled by the relative position of said disks, 105 and a release magnet for allowing the selected lever to become operative to arrest the shaft in a position to print any character. 110

4. In a printing telegraph receiver, the combination of a current distributor, a plurality of circuits connected thereto, magnets in said circuits, a plurality of pivoted disks, one for each magnet and controlled thereby, a rotatable type shaft carrying the characters, a plurality of spring tensioned levers selectively controlled by the relative position of said disks, and a release magnet in one of said circuits operable to allow a selected one of said spring tensioned levers to 120 co-operate with said shaft to present any character for printing. 125

5. In a printing telegraph receiver, a current distributor, a plurality of branch circuits connected thereto, type selecting mag- 130

nets and operation controlling relays in said branch circuits, a rotatable type shaft carrying characters to be selected, means for starting the rotation of said shaft, and a 5 start control relay actuated to prevent the operation of said starting means upon the operation of predetermined operation controlling relays.

In witness whereof, I hereunto subscribe my name this 4th day of January A. D., 1913.

AMOS F. DIXON.
